(57) **CLAIM**

The ornamental design for a speaker assembly, as shown and described.

DESCRIPTION

FIG. 1 is a top plan view of a speaker assembly;

FIG. 2 is a front elevational view thereof;

FIG. 3 is a bottom view thereof;

FIG. 4 is a right-side elevational view thereof;

FIG. 5 is a rear elevational view thereof;

FIG. 6 is a left-side elevational view thereof; and,

FIG. 7 is a front isometric view thereof.

The broken lines are for environmental purposes only and form no part of the claimed design.

The claimed speaker assembly is used to intensify sound, such as music, speech, etc., and make it audible throughout a room, hall, or the like.
